DESIGN FOR A GAME DEVICE

Henry Singer, Honolulu, Territory of Hawaii, assignor of one-half to Alice H. F. Lum, Honolulu, Territory of Hawaii

Application June 6, 1940, Serial No. 92,858

Term of patent 14 years

To all whom it may concern:

Be it known that I, Henry Singer, a citizen of the United States, residing at Honolulu, in the county of Honolulu and Territory of Hawaii, have invented a new, original, and ornamental Design for a Game Device, of which the following is a specification, reference being had to the accompanying drawing, forming part thereof.

The characterizing feature of the invention resides in a game device consisting of the configuration and arrangement of the parts as illustrated and as comprised of a central flat member with a relatively large opening therein and having radiating therefrom relatively short and broad points on the outer end of which are directly mounted headed members which extend beyond the opposite flat faces of the points and central member as shown.

I claim:

The ornamental design for a game device, as shown and described.

HENRY SINGER.
